(57) **CLAIM**

The ornamental design for a dispenser, as shown and described.

DESCRIPTION

FIG. 1 is a top, front and right side perspective view of a dispenser showing my new design;

FIG. 2 is a top view thereof;

FIG. 3 is a left side elevational view thereof;

FIG. 4 is a rear elevational view thereof; and,

FIG. 5 is a bottom, rear perspective view.

The broken-line disclosure in the views is understood to be for illustrative purposes only and forms no part of the claimed design.
